(57) CLAIM

The ornamental design for a tail configuration for a jet airplane, as shown and described.

DESCRIPTION

FIG. 1 is a perspective view of the inventive tail configuration for a jet airplane;

FIG. 2 is a top plan view of the tail configuration for a jet airplane;

FIG. 3 is a front plan view of the tail configuration for a jet airplane;

FIG. 4 is a back plan view of the tail configuration for a jet airplane;

FIG. 5 is a side plan view of the tail configuration for a jet airplane, with the opposite side being a mirror image thereof; and,

FIG. 6 is a bottom plan view of the tail configuration for a jet airplane.

Other portions of the jet airplane are shown in hidden lines. These form part of the environment of the present invention but are not part of the claimed invention.
